UNITED STATES PATENT OFFICE

JULIUS S. JUDELL, OF MILWAUKEE, WISCONSIN, ASSIGNOR TO THE MILWAUKEE FLUSH VALVE COMPANY, OF MILWAUKEE, WISCONSIN, A CORPORATION OF WISCONSIN

COMBINATION FIXTURE

Application filed January 25, 1926. Serial No. 83,445.

This invention relates to combination fixtures and more particularly to combined tub and shower fixtures.

It contemplates more especially the provision of a unitary control for selectively admitting a proportioned mixture of hot and cold water to either the tub or shower, the control being preferably so constructed and arranged as to regulate the amount of water delivered to either the tub or shower.

One object of the present invention is to improve the construction and operation of combination fixtures of the character mentioned.

Another object is the provision of an improved valve mechanism for directing and regulating the flow of water to any of a plurality of parts of a combined fixture.

A further object is to provide means including a shower attachment, which can be readily combined with a tub already installed, and through which water may be delivered to either the shower or tub selectively.

Other objects and advantages will appear from the following description of an illustrative embodiment of the present invention.

In the drawings:

Figure 1 is a view of a combined tub and shower fixture constructed in accordance with the present invention.

Fig. 2 is a sectional view taken substantially along line 2-2 of Figure 1.

Fig. 3 is a sectional view taken substantially along line 3-3 of Figure 2.

Fig. 4 is a view of a pilot valve shown in Figure 2.

Fig. 5 is a view similar to Figure 1, showing a modified combination fixture.

Fig. 6 is a sectional view taken substantially along line 6-6 of Figure 5.

Fig. 7 is a sectional view taken substantially along line 7-7 of Figure 5.

Fig. 8 is a view similar to Fig. 4, showing a modified form of pilot valve which may be employed in either type of fixture.

The fixture illustrated in Figures 1 to 4 comprises the usual hot and cold water supply pipes 10 and 11, connected to the opposite ends of a cross pipe 12, through the usual regulating valves 13 and 14. The pipe 12 constitutes a mixing chamber for receiving hot and cold water in proportions determined by the setting of the valves 13 and 14. Pipes 10, 11 and 12 are shown disposed within the wall 15 with the valve handles projecting from the wall. A pipe 16, in open communication with pipe 12 through the usual T-fitting 17, leads through the wall to a bath tub faucet 18 in accordance with standard practice.

The faucet 18 is of novel construction. It is provided with a longitudinal bore 19 having diametral ports 20 and 21 leading therefrom. The upper port 20 communicates with a pipe 22 screwed into the faucet and constituting a support for a shower head 23. The lower port 21 communicates with a passage 24 leading lengthwise of the faucet to the discharge end 25 thereof through which water is delivered to the tub 26. The faucet is supported by and fed from the pipe 16 through an appropriate union 27.

A valve 28 controls communication between the pipe 16 and the ports 20 and 21. The valve shown is provided with a hollow cylindrical head 29 rotatable within the bore 19, and open to the pipe 16. A substantially rectangular opening or port 30 through the wall of the hollow valve head cooperates with the ports 20 and 21 to control the admission of water from pipe 16 to pipe 22 or to passage 24, selectively. The arrangement is such that with the valve in the position shown in Figure 2, port 20 is closed by the wall of the valve and port 21 is open to pipe 16 through port 30 and water is supplied to the tub only. By rotating the valve through one hundred and eighty degrees, port 30 is made to register with port 20 and port 21 is closed, so that water from pipe 16 flows to the shower head.

only. By rotating the valve slightly from either of the extreme positions just described the rate of flow through ports 21 and 30 may be regulated while the other port 20 remains closed, or the rate of flow through ports 20 and 30 may be regulated while the other port 21 remains closed. It is thus possible to regulate the rate of flow to either the tub or shower while the flow to the other is shut off. In an intermediate position of the valve, both ports 20 and 21 are substantially closed.

It will be noted that when both valves 13 and 14 are open, the hot and cold water supply pipes 10 and 11 are in communication through the cross-pipe 12, and, unless the water in pipe 12 were free to escape, the hot water from pipe 10 would tend to pass through pipe 12 and back up into the cold water pipe 11. To avoid this condition provision is preferably made for by-passing a small amount of water from the pipe 12 to either the shower or tub in the intermediate position of the valve 28. This is accomplished in the faucet shown by making the port 30 wide enough so that it is impossible to completely close both ports 20 and 21 at the same time when the valve is in the intermediate position. To prevent this leakage of water through the shower or tub the operator will find it necessary to shut off both valves 13 and 14, and in so doing will avoid the undesirable condition above mentioned.

In order to maintain a tight fit between the valve head 29 and bore 19 the hollow head is rendered radially resilient and expandable by slitting the same transversely as at 31, and by extending the port 30 the entire length of the hollow head. The diameter of the hollow head is normally slightly greater than that of the bore 19, so that when forced into the bore the head is contracted slightly and maintains a resilient pressure against the wall of the bore. To insure the resilient reactive pressure between the coating ports, a curved metal spring 32 is positioned in the hollow head 29 so as to expand the valve head, thereby causing the latter to resiliently bear against its seat.

The valve 28 may be controlled by any appropriate means such as a handle 34 secured to an appropriate stem 35 fixed to the valve 28 and projecting from the end of the faucet.

The combined faucet and shower head above described may be readily applied as a unit to standard bath tub fixtures already installed, merely by removing the old faucet from the pipe 12 and substituting the new.

The fixture illustrated in Figures 5, 6, 7 and 8 is similar to that just described but is designed primarily for new installations. This fixture includes a cross pipe 12' for connection with the usual hot and cold water supply pipes 10' and 11' through the usual regulating valves 13' and 14'. The pipe 12' is in this instance provided with a special

fitting 36 intermediate the ends thereof. A passage 37 through the fitting maintains communication between the ends of the pipe 12'. The fitting is also provided with a cylindrical bore 19' for receiving the hollow head 29' of a valve 28' substantially identical with that hereinabove described. The interior of the head 29' is open to the passage 37 through a port 39.

The valve head 29' in this instance, has a port 30' through the wall thereof adapted to register with either of two diametral ports 20' or 21' leading upwardly and downwardly from the bore 19'. The upper port 20' communicates through a pipe 22' with a shower head 23' and the lower port 21' communicates through a pipe 40 with the faucet 18' of a bath tub 26'.

The arrangement is such that with the valve in the position shown port 30' registers with port 21' and the mixture of hot and cold water from the pipe 12' passes through passage 37, ports 39, 30', and 21' and pipe 40 to the faucet 18'. By turning the valve through one hundred and eighty degrees from this position port 30' registers with port 20' and the water passes up through pipe 22' to the shower head. A small hole 41 through the wall of the valve head 29' at one side of port 30' permits water to pass slowly into pipe 22' or 40 when the valve is in the intermediate position. The operator will find it necessary to shut off both valves 13' and 14', and in so doing will avoid this leakage of water through the shower or tub. A tight fit is maintained between the valve head 29' and the bore 19' by radially slitting the hollow head transversely at 31' and longitudinally as at 42. This modified form of valve as well as others may be substituted for the valve shown in Figure 4 and vice versa, since the specific valves described are selected for illustrative purposes only.

It will be noted that in the fixture just described all of the piping, including the fitting 36, is hidden within the wall 15'.

Various changes may be made in either embodiment of the invention hereinabove specifically described without departing from or sacrificing the advantages of the invention as defined in the appended claims.

I claim:

1. In a combination fixture, a valve body, a cylindrical seat in said body, a valve having a hollow cylindrical head fitted for rotation in said seat, a pair of ports in said seat diametrically positioned, a longitudinal slot in said cylindrical head forming a port for selective cooperation with either of said pair of ports to control the rate of flow therethrough, a transverse slot at the base of said hollow cylindrical head serving with said longitudinal slot to bifurcate said head, and an arcuate spring in contact solely with the inner wall of said hollow cylindrical head to maintain the bifurcated portions thereof in con-

tact with said seat to form a leak-proof valve.

2. In a combination fixture, a valve having a hollow cylindrical head, a cylindrical seat for said valve, a pair of ports in said seat, 5 a longitudinal slot in said hollow cylindrical head forming a port therein, a transverse slot at the base of said longitudinal slot serving to bifurcate said hollow cylindrical head, and an arcuate spring in contact solely with the inner wall of said hollow cylindrical head to maintain the bifurcated portions thereof in contact with said seat to form a leak-proof valve.

In witness whereof, I hereunto subscribe
15 my name this 22 day of January, 1926.

JULIUS S. JUDELL.
